Samuel M. Houck,
By H. A. Coulombe
Attorney.

UNITED STATES PATENT OFFICE.

SAMUEL M. HOUCK, OF SPRINGFIELD, OHIO.

WICK-TRIMMER.

SPECIFICATION forming part of Letters Patent No. 417,031, dated December 10, 1889.

Application filed June 6, 1889. Serial No. 313,339. (No model.)

To all whom it may concern:

Be it known that I, SAMUEL M. HOUCK, a citizen of the United States, residing at Springfield, in the county of Clark and State 5 of Ohio, have invented certain new and useful Improvements in Wick-Trimmers, of which the following is a specification, reference being had therein to the accompanying drawings.

10 This invention relates to certain new and useful improvements in lamp-wick trimmers; and the invention consists, essentially, of two bars pivoted together and forming each at one side of the pivot suitable handles and at the 15 other side of the pivot suitable jaws, which respectively carry a straight-edged and a serrated-edged blade, which act in conjunction with each other; and the invention further consists in providing an adjustable pivot for 20 the device, so that the jaw carrying one blade may be adjusted to move such blade nearer to the other blade, so that they will properly lap each other when they are in cutting position; and the invention further consists in 25 placing the handles well to one side of the blades, so as to place the blades in a horizontal position across the lamp-wick without raising the hand so high; and the invention further consists of certain details of construction 30 hereinafter fully specified.

In the accompanying drawings, forming a part of this specification, and on which like reference-letters indicate corresponding parts, Figure 1 represents my improved lamp-wick 35 trimmer in side elevation; Fig. 2, an edge view thereof; Fig. 3, a sectional view on a larger scale; Fig. 4, a detail perspective view of the serrated blade, and Fig. 5 a detail perspective view of the pivot-block.

40 The letters A and B respectively designate two bars of metal formed into handles C, normally distended or held apart by the interposition of strips D, of resilient metal, secured to the handles and opposing each other near the center, as shown. These bars are each mortised about one-half their thickness and lapped across each other, as usual in constructing pinchers and pliers, and the bar A is provided with a slot E, to which is slidably 45 fitted the shank of the pivot-block F. A pivot-screw G passes through a hole in the

bar B and screws into the pivot-block F, as shown in dotted lines in Fig. 3. The pivot-block is adjusted back and forth in the slot E by means of an adjusting-screw H, mounted 55 in the head of said block, and rotatably but non-slidingly connected with the bar A by fitting an opening therein and receiving a pin I in an annular groove J formed in the screw. By manipulating the screw H the bar 60 A is adjusted lengthwise with respect to the bar B, and the blades carried by the jaws of these bars, as hereinafter described, are thereby adjusted with respect to each other, so that one will pass to the inside and closely 65 against the other, as they lap in the act of cutting or trimming wicks and other material. These jaws are preferably composed each of two members K K, extending from and forming a part of the bar A, and of members L L, extending from and forming a part 70 of the bar B. To the members K is secured, by screws M or otherwise, a blade O, having a straight cutting-edge and shouldered so as to more snugly fit against the members K. 75 To the members L is secured a serrated blade P. The inner side of the blade O is formed on a straight line, and the outside of the blade P is formed in the arc of a circle from the pivot center. The result is that when the 80 handles C C are brought together the blades pass each other in close contact. The blade O is beveled from the outside and the blade P from the inside, as seen in Figs. 1 and 4, the serrations being beveled on the inner side, 85 as seen in the latter figure. The result is that the two sharp edges overlap each other in intimate contact when the jaws are brought together, while the serrated form of the cutting-edge of the blade P gives it a draw cut, 90 which is of marked advantage in manipulating the device. The blade O may be adjusted nearer to the blade P in a radial direction by removing it and drawing a file across the ends of the members K; but the preferred 95 means of adjusting the blades with respect to each other is that already described, through the manipulation of the screw H. Stops Q are provided to prevent the hand from slipping too much toward the pivotal point when 100 manipulating the device.

In order to avoid the necessity of having

to raise the hand immediately above the wick when using the device in an inverted position, I have deflected the handles C C to one side, as seen in Fig. 2, so that when the device is inverted the cutting-edges of the blades may occupy substantially a horizontal position, while the handles are still inclined to accommodate the then position of the hand.

I contemplate sometimes constructing the device with a fixed pivot between the bars, instead of the adjustable screw herein described.

Having thus fully described my invention, what I claim as new, and desire to secure by Letters Patent, is—

1. As an improved article of manufacture, a wick-trimmer consisting of bars forming handles and jaws and pivoted together at a point between such portions, a straight-edged blade carried by one jaw with its cutting-edge substantially in line with the pivot of the bars, and a serrated-edged blade carried by the other jaw and arranged with its cutting end along which the serrations are formed in substantial alignment with said pivot.

2. As an improved article of manufacture, a wick-trimmer consisting of bars forming handles and jaws and pivoted together at a point between such portions, one bar being slidably connected to the pivot, a straight-edged blade having its inner side straight and beveled from the outer side, carried by one jaw, and a serrated-edged blade curved on the outer side and beveled from the inner side and carried by the other jaw.

3. As an improved article of manufacture, a wick-trimmer consisting of bars forming handles and jaws, a block carried by one bar and adjustable with respect to the other bar,

and an adjusting-screw for adjusting the block 40 back and forth, and a pivot passing through the other bar and connecting with said block, and a blade carried by each jaw and co-operating with each other to effect a cutting action when the handles are forced toward 45 each other.

4. As an improved article of manufacture, a wick-trimmer consisting of bars forming handles and jaws, a pivot-screw fitted to one bar, a slot in the other bar, a block slidingly 50 fitted to said slot, and an adjusting-screw engaging with the block and rotatively connected with the slotted bar, and a blade carried by each jaw.

5. A blade for a wick-trimmer, consisting 55 of a plate provided with serrations at one edge, the serrations being beveled on their inner side and curved on the outer face or surface which works against the opposing blade, substantially as shown and described. 60

6. As an improved article of manufacture, a wick-trimmer consisting of two bars pivoted together and forming handles at one side and jaws at the other side, the jaws being arranged so that those of one bar are in the 65 same plane as those of the other bar, a blade secured to one of said jaws and beveled at its cutting-edge on the outer side, and another blade secured to the other jaw and beveled at its cutting-edge on the inner side, the 70 said plates having their cutting-edges disposed crosswise to the handles.

In testimony whereof I affix my signature in presence of two witnesses.

SAMUEL M. HOUCK.
